(57) **CLAIM**

The ornamental design for a vehicle, toy, and/or replicas thereof, as shown and described.

DESCRIPTION

This application contains subject matter related to the following co-pending U.S. design patent applications:

Application Ser. No. 29/413,273, filed herewith and entitled "Headlight for a Vehicle"; and,
Application Ser. No. 29/413,275, filed herewith and entitled "Taillight for a Vehicle".

FIG. 1 is a left, front perspective view of a vehicle, toy, and/or replicas thereof according to our design;

FIG. 2 is a left, rear perspective view thereof, the right, rear perspective view being mirror symmetrical;

FIG. 3 is a left side view thereof;

FIG. 4 is a right side view thereof;

FIG. 5 is a front view thereof;

FIG. 6 is a rear view thereof; and,

FIG. 7 is a top view thereof.

The broken lines are for illustrative purposes only and form no part of the claimed design.
